UNITED STATES PATENT OFFICE.

THOMAS C. JOHNSON, OF NEW HAVEN, CONNECTICUT, ASSIGNOR TO
WINCHESTER REPEATING ARMS CO., OF NEW HAVEN, CONNECTI-
CUT, A CORPORATION.

AUTOMATIC FIREARM.

SPECIFICATION forming part of Letters Patent No. 769,089, dated August 30, 1904.

Application filed December 26, 1903. Serial No. 186,541. (No model.)

To all whom it may concern:

Be it known that I, THOMAS C. JOHNSON, of New Haven, in the county of New Haven and State of Connecticut, have invented a new and useful Interchangeable-Barrel Automatic Firearm; and I do hereby declare the following, when taken in connection with the accompanying drawings and the numerals of reference marked thereon, to be a full, clear, and 10 exact description of the same, and which said drawings constitute part of this specification, and represent, in—

Figure 1, a broken view, partly in elevation and partly in vertical longitudinal section, of 15 the gun-frame structure of a take-down gun embodying my invention; Fig. 2, a detached broken view, in side elevation, of one of the interchangeable barrels provided for use in my improved gun; Fig. 3, a broken view, partly 20 in side elevation and partly in vertical section, of the gun-frame structure, showing the barrel extension pushed forward and the barrel partly unscrewed; Fig. 4, a broken view, partly 25 in side elevation and partly in section, showing the fore-stock and magazine detached and the magazine partly drawn forward out of the fore-stock; Fig. 5, a broken view, partly 30 in plan and partly in horizontal section, showing the retention in the gun-frame of the barrel extension by the breech-block through the medium of the ejector carried thereby; Fig. 6, a 35 detached cross-sectional view of the barrel extension (shown in full size) on the line *a b* of Fig. 3 and looking in the direction of the arrow *c* thereon; Fig. 7, a detached view of the barrel-closing spring.

Heretofore the huntsman has generally provided himself with a double-barreled shotgun having a cylinder-bore barrel for use in killing small game and a choke-bore barrel for 40 use in killing larger game, or he has provided himself with two guns, one having a cylinder-bore barrel and the other a choke-bore barrel. It has, however, been proposed to produce a 45 shotgun provided with two or more interchangeable barrels; but these guns have necessitated the interchange of more parts than simply the barrels themselves and have been

objectionable on that account, as well as expensive and heavy.

The object of my present invention is to produce a tubular-magazine automatic firearm of a simple, reliable, compact, and convenient construction in which two or more barrels may be easily and quickly interchanged without the use of special tools or the exercise of any skill and without the interchanging of any parts other than the barrels themselves, whereby with the minimum of expense, of load to carry, and of inconvenience the huntsman is provided, in effect, with a cylinder-bore shotgun and a choke-bore shotgun or, if desired, with a cylinder-bore shotgun and shot-guns having different degrees of choke.

With these ends in view my invention consists in a tubular-magazine automatic firearm having certain details of construction and combinations of parts, as will be hereinafter described, and pointed out in the claims.

For the illustration of my invention I have 70 chosen a gun of the construction shown and described in my pending patent application, filed June 29, 1903, and serially numbered 163,630. I do not limit myself, however, to utilizing my invention in a gun of that particular construction, as it may be embodied in 75 guns different therefrom in many particulars.

In carrying out my invention as herein shown the gun is furnished with a cylinder-bore barrel 2 and one choke-bore barrel 3; 80 but, if desired, the gun may be furnished with two or more choke-bore barrels having different degrees of choke. The barrel 2 is provided at its breech end with cross-sectionally square threads 4 and the barrel 3 with cross-sectionally square threads 5, these threads being adapted to take into corresponding threads 6, formed in the front end of the barrel extension 7, which is normally located within the gun-frame 8, in which it recoils with the 90 barrel. As shown, the cylinder-bore barrel 2 is in the gun and the choke-bore barrel 3, provided at its threaded end with a protecting sleeve 9, screwed on over its threads for the protection of the same. This sleeve will be 95 shifted from one barrel to the other, so as to

be kept on the barrel not in use. If more than one extra barrel is used, a corresponding number of these sleeves will be needed. Each barrel is provided with an integral depending barrel-stop 10 in the form, as shown, of a ring adapted in diameter to slide freely over the tubular magazine 11, which is passed through it from front to rear, the magazine being furnished at its rear end with threads 11^a, adapting it to be screwed into and unscrewed from a threaded magazine-opening 12, formed in the lower portion of the front end of the gun-frame 8. To adapt the magazine to be readily and easily screwed into and unscrewed from the gun-frame by hand and without the use of special tools, it is provided at its forward end with a fixed or integral annular take-down flange 13, formed, as shown, with several radial holes 14 for the reception of a heavy pin (not shown) or the short studs or pins of a spanner-wrench. The said take-down flange 13 also forms a fore-stock tip, for which purpose its rear face is made with an annular recess 15 for the reception of a circular tenon 16 at the forward end of the wooden fore-stock 17, the rear end of which is furnished with a corresponding tenon 18, entering a corresponding recess 19 in the gun-frame and concentric with the magazine-opening 12 therein. Under this construction the fore-stock 17 is supported by the take-down flange 13 and the gun-frame 8, both as to endwise and lateral movement and not by the magazine 11, which, as will be seen by reference to Figs. 1 and 4, clears the fore-stock throughout the length thereof, so that the magazine may be turned freely without binding in the fore-stock, the chamber 17^a of which is larger than the diameter of the magazine. The said magazine 11 is also formed with an integral stop-shoulder 20, positioned upon it so that when the gun is assembled it will be located in front of the barrel-stop 10 of any of the gun-barrels and form an abutment for a buffer in the form of a washer 21, against which the forward face or edge of the barrel-stop 10 impinges to stop the return or forward movement of the gun-barrel under the influence of the barrel-closing spring 22, which encircles the rear portion of the magazine and impinges at its forward end against the rear face or edge of the barrel-stop 10 and at its rear end against the lower portion of the front end of the gun-frame 8.

The passage of the magazine 11 rearward through the barrel-stops 10 of the gun-barrels operates to lock them against turning or working loose under the shocks of use, the magazine constituting, in effect, a bolt for holding the barrels against turning. That being provided against, I preferably form the barrels with cross-sectionally square threads, as already described, because they are stronger and better adapted than cross-sectionally annular threads to be used in situations where

the barrels are not designed to be solidly screwed home by means of a vise and tools, for it is to be understood that in my improved gun the barrels are not to be screwed home so but what they can be unscrewed by hand. In an ordinary gun the barrel must be screwed home solidly, so that it will not turn and work loose when the gun is in use; but, as already explained, this is not necessary in my gun, because the barrel-stop and the magazine form a lock to prevent the barrel from turning. In my gun the barrel may be said to be removably coupled to the gun structure rather than solidly united thereto.

The said barrel extension 7 contains an independently-movable breech-block 23, furnished with a pivotal locking-block 24, which when lifted enters a locking-recess 25, formed in the upper wall of the extension, whereby the said block is locked in its recoil-taking position to the extension, so that the barrel 2, barrel extension 7, and block 23 recoil together. The said locking-block 24 is operated by means of an operating rod or bar 26, the forward end of which is pivotally connected with it and the rear end of which projects sufficiently beyond the rear end of the gun-frame 8 when the gun is taken down, as shown in Fig. 1, to permit it to be seized by the fingers and operated manually for the purpose of unlocking the bolt from the barrel extension, which is thus freed to be moved forward nearly out of the frame preparatory to the detachment of the barrel from the extension, as will be hereinafter described. An ejector 27, mounted in the left-hand side of the forward end of the breech-block 23, coacts with an ejecting-shoulder 28, forming the rear wall of a long clearance slot or groove 29, formed in the inner face of the left-hand wall of the barrel extension, in ejecting the spent shells from left to right out of the barrel extension and through the right-hand wall of the gun-frame. This is the primary function of the ejector 27 and ejecting-shoulder 28; but they also assist in my improved gun in retaining the barrel extension in the gun-frame when the gun is taken down and the barrels are being interchanged. At this time the shoulder 28 of the extension strikes the ejector 27, carried by the breech-block, the lug or stop 30 of which engages with the gun-frame and stops the forward movement of the block, which in turn through its ejector 27 stops the forward movement of the barrel extension, which is thus prevented from coming out of the forward end of the gun-frame. It will thus be seen that when the gun is taken down the ejector 27 constitutes a retainer for the barrel extension and that the lug 30 constitutes a retainer for the breech-block. The said lug 30 corresponds, as I may here mention, to the lug 151 of the "cartridge-controller" shown and described in my said pending application, which may be referred

to for a more detailed description of the construction and operation of the gun so far as the barrel extension, breech-block, ejector, locking-block, and operating-bar are concerned.

Preparatory to interchanging one barrel for another in my improved gun the same must be taken down, so as to separate the gun-frame and the parts organized therewith from the guard frame or tang and the parts organized therewith on the principle of construction shown in my said pending application. In the drawings filed with this application I have considered it unnecessary to show the guard-frame and its coördinated parts and have illustrated only the gun-frame and its coördinated parts, the gun-frame and the guard-frame and their parts forming, as it were, two independent organizations. The gun having been taken down preparatory to interchanging one barrel for another, the magazine is unscrewed from the gun-frame. This is readily and easily accomplished without the use of any tools other than of a simple pin or rod, which is inserted into one of the openings 14 in the take-down flange 13 at the front end of the magazine and using the pin as a lever. Of course a spanner-wrench might be used for the purpose in place of a pin, or the said take-down flange might be made with flattened faces to permit the use of an ordinary wrench. This last suggestion is thought to be too plain to require illustration. When the magazine is unscrewed, so that the threads 11^a at its rear end are cleared from the threads of the magazine-opening 12 in the gun-frame, the magazine and the fore-stock 17 are detached from the gun by drawing them straight forward. The locking-block 24, mounted in the breech-block 23, is now manually drawn downward out of the locking-recess 25 in the barrel extension 7 by means of the operating rod or bar 26, the projecting rear end of which is seized by the fingers. The drawing down of the locking-block into its unlocked position releases the barrel extension and permits the barrel and barrel extension to be pushed forward with respect to the gun-frame 8 by the barrel-closing spring 22 until the shoulder 28 of the barrel extension engages with the ejector 27, carried by the block 23, which is then drawn forward by the barrel and barrel extension until the lug or stop 30, carried by the block, engages with the forward end of the gun-frame, as shown in Fig. 2. By this time the spring will have practically, if not entirely, reached its full extension and may be easily removed if it does not drop out of itself. In either event the barrel extension, though projected from the gun-frame will be retained therein through the medium of the breech-block, which is also retained therein by the engagement of the lug or stop 30 with the frame. The barrel having previously been unlocked by the re-

moval of the magazine is now easily and readily unscrewed from the barrel extension. This is done by hand and without the use of tools, for, as before explained, as the barrel is normally locked against rotation by its depending barrel-stop and the magazine which acts as a bolt it is unnecessary to screw the barrel solidly home. The barrel having been removed from the barrel extension, the other barrel, or, if more than one extra barrel is provided, one of

70

the other barrels, is screwed by hand into the barrel extension. The barrel-closing spring 22 is now restored to its position between the rear face of the barrel-stop and the front end of the gun-frame, the fore-stock is returned to its place, and the magazine is passed from front to rear through the fore-stock and through the barrel-stop of the barrel and entered at its threaded rear end into the threaded magazine-opening in the gun-frame, into which it is screwed home by the use of a pin or spanner-wrench, as before described. Of course the rear end of the magazine can not be entered into the gun-frame until the barrel-closing spring has been compressed, which is done by seizing the barrel and forcing the same rearward, whereby the barrel extension is forced back into the gun-frame. This completes the operation of interchanging one barrel with another in my improved gun, the operation being quickly and easily performed without the use of special tools and without the exercise of any special skill on the part of the huntsman.

90

It is to be particularly noted that no parts of the gun are in duplicate, in which respect my improved gun is different from a proposed construction in which the gun has been provided with interchangeable barrels and barrel extensions.

105

It is apparent that in carrying out my invention some changes from the construction herein shown and described may be made. I would therefore have it understood that I do not limit myself thereto, but hold myself at liberty to make such departures therefrom as fairly fall within the spirit and scope of my invention. It is apparent also that my invention is applicable to the manufacture of interchangeable-barrel rifles, whereby rifle-barrels differentiated in bore may be used in the same gun.

115

Having fully described my invention, what I claim as new, and desire to secure by Letters Patent, is—

120

1. In an interchangeable-barrel tubular-magazine automatic firearm, the combination with the frame thereof, of a recoiling barrel extension mounted in the said frame, a recoiling barrel threaded for being removably mounted in the said barrel extension so as to be interchanged therein with other barrels, a tubular magazine threaded for being removably mounted in the said frame and provided at its front end with a fixed take-down

125

130

flange by means of which it is engaged for being screwed into and unscrewed from the said frame, means depending from the barrel and coacting with the magazine to prevent 5 the barrel from rotating when the gun is assembled, a fore-stock supported at its rear end by the gun-frame and at its forward end by the said take-down flange, and means for retaining the said extension in the frame 10 when the gun is taken down.

2. In an interchangeable-barrel tubular-magazine automatic firearm, the combination with the frame thereof, of a recoiling barrel extension mounted in the said frame, means 15 for retaining the said recoiling barrel extension in the said frame when the gun is taken down, a recoiling barrel threaded for being removably mounted in the said barrel extension so as to be interchanged therein with 20 other barrels, a barrel-closing spring, a tubular magazine threaded for being removably mounted in the said frame and provided at its front end with a fixed take-down flange by means of which it is engaged for being screwed 25 into and unscrewed from the said frame, a stop-shoulder on the magazine, a barrel-stop depending from the recoiling barrel and coacting with the magazine to prevent the barrel from rotation and coacting with the stop- 30 shoulder on the magazine to limit the forward movement of the barrel by the said spring, and a fore-stock supported at its rear end by the frame and at its forward end by the said take-down flange.

3. In an interchangeable-barrel tubular-magazine automatic firearm, the combination with the frame thereof, of a recoiling barrel extension mounted in the said frame, a breech-block, an ejector mounted in the breech-block and coacting with the barrel extension to retain the same in the said frame when the gun is taken down, a stop carried by the said breech-block to retain the same in the said frame when the gun is taken down, a recoiling barrel threaded for being removably mounted in the barrel extension for being interchanged therein with other barrels, a barrel-closing spring, a tubular magazine threaded for being removably mounted in the said frame and provided at its front end with a take-down flange by means of which it is engaged for being screwed into and unscrewed from the frame, a stop-shoulder on the magazine, a barrel-stop depending from the recoiling barrel and coacting with the said stop-shoulder on the magazine for limiting the forward movement of the barrel and coacting with the magazine for preventing the barrel from rotation, and a fore-stock supported at its rear end by the gun-frame and at its forward end by the said take-down flange. 45 50 55 60

In testimony whereof, I have signed this specification in the presence of two subscribing witnesses.

THOMAS C. JOHNSON.
